G. S. MAXWELL,
INTERNAL COMBUSTION ENGINE.
APPLICATION FILED APR. 2, 1917.

1,339,035.

Patented May 4, 1920.

UNITED STATES PATENT OFFICE.

GEORGE S. MAXWELL, OF WASHINGTON, DISTRICT OF COLUMBIA, ASSIGNOR TO A. RALPH SERVEN, TRUSTEE, OF WASHINGTON, DISTRICT OF COLUMBIA.

INTERNAL-COMBUSTION ENGINE.

1,339,035.

Specification of Letters Patent. Patented May 4, 1920.

Application filed April 2, 1917. Serial No. 159,289.

To all whom it may concern:

Be it known that I, GEORGE S. MAXWELL, a citizen of the United States, residing at Washington, in the District of Columbia, have invented certain new and useful Improvements in Internal-Combustion Engines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to internal combustion engines, and has for its object to bring within quick, easy, and convenient control of the operator, the supply, at will, of either an explosive gas or mixture, enriched or not; or an enriched gas supplemented with gas supplied by an ordinary carburetor; or the supply of gasolene or other combustible mixture, either alone or combined with a fixed gaseous agent or substance, to an ordinary carburetor, to furnish the necessary explosive mixture for the engine cylinder, as found desirable or necessary to meet different contingencies or conditions.

To the accomplishment of the foregoing and such other objects as may hereinafter appear the invention involves the disposition of valves in different conduits or passageways operatively connected with one another so that by manipulating an appropriate lever conveniently located within easy reach of an operator the desired valve or valves may be actuated so as to open or close or adjust the same so as to supply the particular gas or mixture or material desired to meet the exigencies or conditions existing at any particular time.

One form of the apparatus, suitable for purposes of illustration, is shown diagrammatically, in the accompanying drawing, wherein some parts are shown in elevation and other parts in section.

In the drawing the numeral 1 designates a carburetor of any preferred suitable construction; 2 the intake pipe to the carburetor; 3 the throttle; and 4 the manifold intake between the carburetor and explosive engine (not shown) all of which elements and their ordinary purpose and operation are well known and need not be further described.

An auxiliary intake pipe 5 is illustrated

as in communication with the carburetor 1 at the point of location of the throttle 3 but may be otherwise connected up with the manifold intake leading to the explosive engine (not shown). The auxiliary intake 5 communicates at one end with an air intake 6 and at the junction of the two pipes is a suitable valve 7 to control the port 8 between the pipes. This valve is illustrated as 60 carried by a swinging arm 10 under the influence of a spring 11 whose tension may be varied by an adjusting screw 12. The valve 7 also serves to normally close the discharge end of a pipe 13 leading from a reservoir 14 designed to contain a suitable volatile combustible agent or mixture, for instance gasolene, supplied to the reservoir through a cap covered opening 15 or otherwise. The reservoir 14 communicates with a reservoir 70 16 in which is stored an explosive gas under compression, the gas being a fixed gas (preferably an illuminating gas, or acetylene), or volatile explosive or combustible fluid or mixture, and which is designed to enrich 80 the volatile combustible material contained in the reservoir 14 so as to produce a highly efficient combustion fuel for the explosive cylinder of the engine. Between the two reservoirs, for instance in the conduit or 85 piping 17 through which communication is established between the reservoirs, is placed a pressure regulating or reducing device for maintaining a substantially uniform or constant pressure in the reservoir 14 under different or varying pressures in the reservoir 16. This pressure regulator 18 is divided 90 by a partition 19 into two compartments 20 and 21, one of which is provided with an elastic diaphragm 22. The upper compartment communicates by one branch of the conduit 17 with the compressed gas storage reservoir and by the other branch with the volatile combustible material reservoir 14, and the upper portion of the reservoir 14 100 is in communication through a pipe 23 with the chamber 21 of the regulator 18 beneath the diaphragm therein. The gas receiving orifice 24 of the regulator is opened or closed by a valve 25, working through partition 19 and bearing against a lever 26 at one end resting on a stud 27 attached to the elastic diaphragm 22 so as to be lifted by a predetermined or excess of pressure in chamber 21 beneath the diaphragm and at such time 110 close orifice 24 and cuts off supply of compressed gas from reservoir 16 until pressure

in chamber 21 is reduced, whereupon lever 26 and valve 25 will fall so as to open inlet orifice 24 for supply of additional compressed gas to the chamber 20 from which it will pass through pipe 17 to reservoir 14 and enrich the volatile combustible material therein. The pressure in reservoir 14 is ordinarily slightly above atmospheric pressure and so maintained by valve 7 keeping closed the discharge end of pipe 13 by atmospheric pressure in the auxiliary intake plus the tension of spring 11. When there is reduction of pressure in the auxiliary intake sufficient to overcome the resistance of spring 11 the valve 7 will be drawn away from the discharge end of pipe 13 and from port 8, whereupon the enriched combustible gas from the reservoir 14 as well as air from the intake 6 will pass into the auxiliary intake 5 and from thence to the manifold intake 4, and to the engine cylinder (not shown) and there be exploded in the usual way. When the suction in the auxiliary intake 5 created by the engine is reduced sufficiently, the pressure of spring 11 will close valve 7 and the supply of gas from reservoir 14 and air from intake 6 will be cut off until variation of pressure in the auxiliary intake is again sufficient for the automatic opening 30 of the valve for additional supply of explosive gas and air to the engine, and thus the operation is repeated in succession.

The reservoir 14 is in communication with the carbureter 1 by means of an emergency 35 pipe or conduit 28 so that if from any cause the supply of enriched gas fails, or if it be desired to either supplement it or supplant it with the volatile combustible material in reservoir 14, enriched by a more or less ad- 40 mixture therewith of the enriching gas, or not, the combustible material in reservoir 14 may in such emergency be delivered to the carbureter 1 and carbureted therein as under ordinary carburation.

45 The apparatus so far described is not claimed herein but is given as one form of apparatus in which the present invention may be embodied and in connection with which and to effect the results hereinbefore 50 described the novel features now to be described are especially well adapted.

In the pipe 13 for the supply of the enriched combustible gas from the reservoir 14 is placed a multiple-way cock or valve 29 55 and in the emergency fuel supply pipe leading from the reservoir 14 to the carbureter 1 is placed a multiple-way cock or valve 30. These two cocks or valves will be connected one with the other by suitable means enabling them to be conjointly operated, for instance by a connecting rod 31 with which the arms or levers 33 and 34 of the respective valves are connected, and the connecting rod is actuated by suitable means as for instance by a manipulating lever of any suit-

able type, such as a lever 35, positioned at a point within convenient reach of the operator. The ports in these multiple-way cocks or valves are so formed that in two positions of each valve the passage-way controlled by each will be open and in a third position closed; and the valves are so adjusted or positioned that when the two valves are moved to one position the port in one will be open and in the other closed; when moved to a second position the port in one will be open and the port in the other previously closed will be open; and when moved to a third position the port in one previously open will be closed and the port in the other will remain open. For instance, as illustrated, when the lever 35 is in position 1^a indicated on the scale, valve 29 will be open so that gas only, enriched or not, will pass from reservoir 14 through pipe 13 leading to intake 5, and valve 30 in pipe 28 leading from the reservoir to the carbureter 1 will be closed; when the lever is moved to position 2^a indicated by the scale, valve 29 will still be open for the passage of gas from reservoir 14 and 90 valve 30 will be open for the passage of gasoline from reservoir 14 to carbureter 1 to supplement the gas from reservoir with the gasoline carbureted in carbureter 1 to form the explosive mixture or fuel; and when lever 35 is moved to position 3^a indicated by the scale, valve 29 will be closed 95 so that there will be no supply of gas through pipe 13 to intake 5, and valve 30 in emergency pipe 28 will remain open so that 100 gasoline from reservoir 14 enriched by the admixture of fixed gas from reservoir 16, or not, as conditions may exist, is supplied to carbureter 1 to be carbureted therein and furnish the explosive mixture or fuel for the 105 engine cylinder. It will thus appear that by conjoint action of the two valves an enriched gas or mixture, under pressure control, is automatically supplied to the engine cylinder, without supply of liquid gasoline 110 or combustible mixture to a carbureter for carburation as commonly practised; that when necessary or desirable the gaseous combustible fuel, more or less enriched, may be supplemented by the vapors or gas evolved 115 from gasoline or other liquid volatile combustible material supplied to and carbureted in a carbureter; and thirdly, that the furnishing of an enriched gas, under pressure control, may be entirely supplanted by the 120 supply of gasoline or other liquid combustible material to an ordinary carbureter to furnish the explosive fuel for the engine cylinder. These possibilities are all under the direct control of the operator and are 125 brought into play by him, at will, by the manipulation of valves under his control. The starting of the engine and its continued operation under unfavorable conditions and at a saving of fuel expense, and with in- 130

creased efficiency and under quick and easy control of the operator are all obtained by reason of the novel features described.

Having described my invention and set forth its merits, what I claim is:

1. In internal combustion engines, a reservoir for a volatile combustible agent, a conduit for conducting gas from the reservoir, a conduit for conducting the volatile agent from the reservoir, valves for controlling the discharge through the conduits, and means connecting one valve with the other to open one as it closes the other.

2. In internal combustion engines, a reservoir for a volatile combustible agent, a conduit for the passage of gas from the reservoir, a conduit for the passage of the volatile agent from the reservoir, valves for controlling the discharge through the conduits, and means for actuating said valves at will to open one as it closes the other for the discharge of the gas or the volatile agent, as described.

3. In internal combustion engines, a reservoir for a volatile combustible agent, a conduit for the passage of gas from the reservoir, a conduit for the passage of the volatile agent from the reservoir, valves for controlling the discharge through the conduits, and means for actuating said valves, one of the valves being formed for discharge through its conduit in two positions of the valve and the other for closure of discharge through its conduit in an open position of the other valve.

4. In internal combustion engines, a reservoir for a volatile combustible agent, a conduit for the passage of gas from the reservoir, a conduit for the passage of the volatile agent from the reservoir, valves for controlling the discharge through the conduits, and means for actuating said valves, one of said valves being formed for discharge through its conduit in two positions of the valve and closure of discharge in another position, and the other valve formed for closure of discharge through its conduit in two discharge positions of the first mentioned valve and for discharge in the closed position of the other valve.

5. In internal combustion engines, a reservoir for a volatile combustible agent, a conduit for the passage of gas from the reservoir, a conduit for the passage of the volatile agent from the reservoir, valves for controlling discharge through the conduits, and means for connecting one valve with the other, each valve being formed for discharge through its conduit in two positions of the valve and closure of discharge in another position, the closed position of one valve corresponding to an open position of the other valve.

In testimony whereof I affix my signature in presence of two witnesses.

GEORGE S. MAXWELL.

Witnesses:

ROSE M. SEFTON,
EDA S. WOLFF.
